United States Patent Office

Des. 208,408

Patented Aug. 29, 1967

208,408

LOUD SPEAKER ENCLOSURE

Bernard A. Cousino, Toledo, Ohio, assignor to Orrtronics, Inc., Toledo, Ohio, a corporation of Alabama

Filed Nov. 8, 1965, Ser. No. 88,034

Term of patent 14 years

(Cl. D26—14)

FIG-1-

FIG-2-

FIG-3-

FIG-4-

FIG. 1 is a front view in perspective of a loud speaker enclosure showing my new design; the portions shown in broken lines disclosed in this figure are intended to indicate conventional perforations. The dominant features of my design reside in the portions shown in full lines;

FIG. 2 is a top perspective view thereof;

FIG. 3 is an end elevational view thereof; and

FIG. 4 is a top or plan view thereof.

I claim:

The ornamental design for a loud speaker enclosure, as shown and described.
